UNITED STATES PATENT OFFICE.

ULYSSES S. SMITH, OF SACRAMENTO, CALIFORNIA.

AUTOMATIC AIR-BRAKE-PRESSURE ADJUSTER.

No. 883,917.

Specification of Letters Patent.

Patented April 7, 1908.

Application filed February 12, 1907. Serial No. 357,101.

To all whom it may concern:

Be it known that I, ULYSSES S. SMITH, a citizen of the United States, residing at Sacramento, in the county of Sacramento and State of California, have invented certain new and useful Improvements in Automatic Air-Brake-Pressure Adjusters; and I do declare the following to be a full, clear, and exact description of the same, such as will enable others skilled in the art to which it appertains to make and use the same, reference being had to the accompanying drawings, and the characters of reference marked thereon, which form a part of this specification.

This invention relates to improvements in means of adjusting automatically the pressure on air-brakes used in connection with railway rolling stock, and particularly on freight cars, my object being to produce a means whereby the braking pressure on all cars may be made uniform according to their weight whether empty or loaded. This object I accomplish by means of an auxiliary cylinder connected to the brake cylinder of the air-brake, a tension spring regulated piston arranged in said cylinder, and a means for regulating the tension of said spring by the weight of the car; also by such other and further construction as will appear by a perusal of the following specification and claims.

In the drawings similar characters of reference indicate corresponding parts in the several views.

Figure 1 is a side elevation of about one half a freight car, showing my improved device arranged thereon. Fig. 2 is a side elevation enlarged of the device partly in section. Fig. 3 is side elevation of a tension spring regulator employed in connection with the improved device.

1 designates a car having the usual air-brake attachment.

2 is the reservoir of the air-brake and 3 is the brake cylinder.

Connected to the brake cylinder 3 by means of a passage 4^a is an auxiliary cylinder 4 in which is an elongated slot or port 5 extending transversely thereof as shown.

Threaded into the rear end of the cylinder 4 is a plug 6 having a shoulder 7 on its inner end and a square shoulder 8 on its outer end, said plug and its parts having an interior orifice 9. And in this orifice 9 is a rod 10 provided within the cylinder with a shoulder 11 bearing against the sides of said cylinder

and against the shoulder 7. The inner end of said rod 10 is provided with a sleeve 12 in which is slidably arranged a rod 13 of a piston 14 operating in said cylinder in front of said slot 5. Bearing between the said piston 14 and shoulder 11 is a tension spring 15 for the purpose as will appear.

In the outer end of the rod 10 is a slot 10^a, and 16 is a lever pivoted to the under side of the car and extending through said slot 10^a. A spring 17 is connected to the lower end of said lever and to the under side of the car, and operating to maintain the lever yieldably in withdrawn position, as hereby explained.

Pivottally mounted on the bottom of the car over one of the axles 18 of the wheels of the said car, is a depending arm 19 having a slot 20 at its lower end. Pivoted on said arm 19 is a lever 21 connected at one end by a rod or cable 22 to the free end of the lever 16 and connected at the other end by a link 23 to a wheel 24 slidably journaled in the slot 20. Formed as a component part of said lever 21 is a curved ratchet rack 21^a with which a pawl 25 pivotally secured to the arm 19, engages. A spring 26 holds said pawl 25 in engagement with said ratchet. A wire cable 27 is connected with the said pawl 25 and extends thence over a pulley 28 to the top of a lever 29, the lower end of said lever extending into the path of the outer terminal of the piston rod 30 of the brake cylinder.

In using the device the plug 6 is adjusted by means of the squared portion 8 until the shoulder 7 pressing against the shoulder 11 causes the spring 15 to be of such tension that it will permit all air from the brake cylinder 3, save and except enough to brake the empty car, say fifty pounds, to pass through the port 4^a, and thence displace the piston 14 and then pass to the atmosphere through the port 5. Thus when the empty car is braked there is no surplus or heavy pressure on the empty car. As the car is loaded the weight causes the bed of the car to lower, thus causing the arm 19 to move downward until the wheel 24 engages with the axle 18, and as the car is loaded still more the wheel 24 moves upward in the slot 20, thus causing the link 23 to drive the outer end of the lever 21 upward and the inner end downward, as shown in dotted lines Fig. 2. This action causes the rod or cable 22 to pull the lever 16 inward, which action causes the rod 10 to be forced inward, thus increasing the tension of the

spring 15 and thereby causing more of the air pressure to be used on the brake, instead of passing out through the port 5. Accordingly as the weight in the car increases the tension 5 of said spring 15 increases, as is apparent, with the results set forth above. The pawl 25 engaging with the ratchet 21^a holds the said spring 15 in the tension described until the brake is applied. When this occurs, the pis- 10 ton head 30 of the brake moves outwardly and engages the lever 29 and moves it outwardly. This action causes the upper part of said lever to pull on the cable 27 thus releasing the pawl 25 from the ratchet rack 21^a and per- 15 mitting wheel 24 to drop if the car has been emptied, and also permitting the spring 15 to resume its normal position, but if the car re- mains loaded, then the weight holds said spring and its parts in their locked positions. 20 Thus it will be seen that I have produced a means whereby, when a car is empty, only sufficient air pressure is retained to brake said car, thus preventing the same from sliding and grinding unnecessarily, which wears flat 25 places on the wheels of the cars and renders them useless. Also a means whereby the braking pressure is gradually increased as the load on the car increases, thus graduat- ing the braking power of the car according 30 to the weight thereof.

Fig. 3 shows a modified means for regulating the tension of the spring 15. In this construction the rod or cable 22 is connected to an L-shaped lever 31 pivotally mounted 35 to an arm 32 pivotally secured in turn to the lower and fixed bolster 33 of the truck of the car, one arm of said L-shaped lever engaging with the under side of the movable bolster 34 of said truck, said lever having a ratchet rack 40 35 similar to the rack 21^a. On an arm 36 forming a part of the arm 32 is pivotally mounted a bell crank 37, one arm thereof engaging with the top of the bolster 34 and the other arm 37^a acting as a pawl and en- 45 gaging with the rack 35. In practice as the car is loaded the bolster 34 moves gradually downward thus causing the lever 31 to pull on the rod 22 and thereby increasing the tension of the spring 15 in the same manner as 50 described in the other arrangement. The pawl finger 37^a engaging with the ratchet rack 35 holds said spring in such position until the load is removed from the car, when the upward rise of the bolster 34 releases it, 55 thus relieving the said tension.

From the foregoing description it will be seen that I have, by my invention, substantially fulfilled the objects set forth in the pre- amble of this specification.

60 It is well known that in a train of cars there are always a few empties intermingled with the loaded cars. Now when it becomes necessary to increase the braking power of a train under the present arrangement, the 65 same braking power is applied to all the cars

indiscriminately. This of course causes the wheels of the empties to slide and wear for a certain distance before the speed is checked or the train stopped. The improved device, however, as described, obviates all the unnecessary braking of empty cars and gradu- 70 ates the braking power according to the weight of the cars. A higher train line pressure is also gained, which admits quicker action on the brakes, both in setting and re- 75 leasing, and power to handle the cars whether empty or loaded, or both, is increased and in emergency cases, greater speed can be made as the power can be carried to brake the cars and keep them more effectually under con- 80 trol.

Having thus described my invention, what I claim as new and useful and desire to secure by Letters Patent is:—

1. The combination with the body of a car 85 having an air brake cylinder depending therefrom, of an auxiliary cylinder, connecting means between the brake cylinder and the auxiliary cylinder, means for permitting the passage of air from said auxiliary cylinder, 90 means operating in said auxiliary cylinder for controlling and regulating said passage of air, and means operated by the movement of the body of the car for automatically actuating said controlling and regulating means. 95

2. In a device of the kind described a cylinder connected with brake cylinder of an air brake, an elongated port in said cylinder, a piston arranged in said cylinder, adapted to open or close said port, a tension spring ar- 100 ranged between the rear of the piston and the rear of the cylinder, and means for automatically regulating the tension of said spring, as set forth.

3. In a device of the kind described a cyl- 105 inder connected to brake cylinder of an air brake, an elongated port arranged in said cyl- inder, a piston arranged in said cylinder and adapted to open and close said port, a spring regulating the position of the said piston by 110 the weight of the vehicle to which the brake is attached, as specified.

4. In a device of the kind described, a ve- 115 hicle, a cylinder connected to brake cylinder of the air brake thereof, an elongated port in said cylinder, a piston arranged in said cylinder, an adjustable plug in the rear of said cylinder, a rod extending through said plug and having a shoulder on its inner end, a spring bearing between said piston and said shoul- 120 der, a slot in the outer end of said rod, a lever pivoted to the underside of the said vehicle and extending through said slot, and means for operating said lever by the weight of the vehicle as set forth. 125

5. In a device of the character described a depending arm pivotally mounted on the underside of a vehicle just above one axle thereof, a slot in the lower end of said arm, a wheel slidably journaled through said slot, an 130

upward link secured to said wheel, a lever pivoted to said arm and secured at one end to said link, a lever pivoted to the under side of a car, a rod or cable connecting said levers, 5 and means in connection with said last named lever for regulating the amount of air passing from the brake cylinder of an air brake, as described.

6. In a device of the character described, a 10 vehicle, a means for permitting the exhaust of air from brake cylinder of an air brake,

means for regulating said exhaust by the weight of the vehicle, and means for regulating said position of said last named means with the piston rod of the braking cylinder, 15 as set forth.

In testimony whereof I affix my signature in presence of two witnesses.

ULYSSES S. SMITH.
